INDIVIDUAL SERVING TRAY

Bobby B. Jones, Ocala, Fla., assignor to Kenneth MacKay, Ocala, Fla.; George L. MacKay, Kenneth H. MacKay, Jr., and Julia F. MacKay, co-executors of Kenneth MacKay, deceased

Filed Aug. 13, 1962, Ser. No. 216,474

4 Claims. (Cl. 108—46)

This invention relates to trays and more particularly to individual serving trays specifically adapted and useful in facilitating the handling and serving of food and beverages at "drive-in" restaurants and the like where meals are eaten in automobiles.

There has long been a need for individual serving trays which could somehow be securely mounted within an automobile so that the inconveniences normally encountered when eating in an automobile wherein all of the food and beverages are served from one large tray and each person is required to hold his own food and drink could be eliminated. With this in mind the serving tray of this invention has been designed to fully overcome such inconvenience and even make it possible to eat within the automobile while it is travelling without the possibility of spilling food or beverage. It is felt that this will greatly enhance this tray's attractiveness to "drive-ins" since people will now be able to buy their meals and proceed upon their way without taking up parking space which is always at a premium.

In view of the foregoing it is an object of this invention to provide an individual serving tray which is readily mountable on a vehicle door or the like wherein there is a space provided between the door's window molding and the glass.

It is another object to provide a tray which is collapsible and readily erectible for use.

It is yet another object to provide a tray adapted to be made from a single blank thus affording maximum economy in material and simplicity in assembly.

It is a still further object to provide a unitary tray held in assembled position by means of locks and tabs stuck from the blank itself.

It is another object to provide paperboard trays which may be shipped flat and assembled at point of use.

The above and other objects will become more apparent when taken in conjunction with the following detailed description and drawings, showing by way of example, a preferred embodiment of the invention.

In the drawings:

FIGURE 1 is a plan view of the completed tray blank prior to assembly;

FIGURE 2 is an end elevational view of the tray in assembled position;

FIGURE 3 is a top plan view of the tray positioned for use on a vehicle door;

FIGURE 4 is a perspective view of the erected tray; and

FIGURE 5 is a cross-sectional view taken along line 5—5 of FIGURE 3.

As illustrated, the tray 10 comprises a top portion 12 having a rectangular opening 14 struck therefrom. The portion cut away in forming rectangular opening 14 is used to form two divider and support panels 16 and 18 hinged about lines 20 and 22 respectively in the top 12. A circular opening 24 is also formed in the top on the side of top opposite that of the rectangular opening 14. As is customary in such devices when an opening is made to receive cups, glasses and the like of varying diameters hemispherical tab-like elements 26 extend inwardly from the edge of the opening to accommodate these various diameters.

A front generally vertical panel 28 extends downwardly from top portion 12. A downwardly directed arcuate

2

bottom portion 30 extends from the lower edge of front panel 28. The bottom portion 30 extends rearwardly and upwardly to meet with the top portion 12 along its rear edge 32. A top spacer panel portion 34 extends 5 rearwardly from the rear edge 32 of the top portion 12. A top flat portion 36 extends from the rear edge of top spacer panel 34. A bottom spacer panel portion 38 projects rearwardly from the rear edge of bottom portion 30 where it meets the top portion 12. This bottom spacer panel 38 is of the same size as the top spacer panel 34 and is fitted firmly thereagainst. Actually, in most instances the two spacer panels are glued together although other means could be used to hold the two together. A bottom flap member 40 projects from the rear edge of bottom spacer panel 38 and is generally coinciding with the top flap 36.

As will be noted the bottom flap 40 is somewhat shorter than top flap 36 and has serrated side edge portions 42 for aiding in holding the flaps in the space between the door molding and the glass member. The top flap 36 and the bottom flap 40 are secured together by spaced bands of adhesive which run perpendicularly with respect to the long dimension of the flaps so as to furnish additional reinforcement for the flaps and thereby make it 20 possible to use paperboard of a somewhat lighter weight.

In order to retain the tray in erected position divider panels 16 and 18 are secured downwardly to engage the bottom 30 so that tabs 50 and 51 will engage and fit into apertures 52 and 53 in said bottom portion. Thus the 30 divider panels 16 and 18 serve a dual function, namely, to act as tray partitions and also to retain the tray in erected position.

The completed blank 60 from which the tray of this invention is formed is shown in plan view in FIGURE 1 and comprises a rectangular portion 62 having divider panels 64 and 65 struck therefrom so as to hinge along lines 66 and 67, respectively, and thereby form a generally rectangular opening 68. In addition, a generally circular aperture 70 is cut in the rectangular portion 62 40 with tabs 72 projecting inwardly from the periphery of the aperture. The rectangular portion 62 is adapted to form the top portion of the tray.

A second rectangular portion 72 extends from forward edge 74 of the first rectangular and is adapted to swing 45 downwardly to form the front vertical panel of the tray. A third rectangular portion 78 extends from edge 76 of second rectangular portion 72. This third rectangular portion 78 is adapted for folding downwardly and then rearwardly and upwardly so that its outer edge 80 will 50 tures 84 and 86 are struck from third rectangular portion 62, thus, forming the bottom of the tray. A pair of apertures 84 and 86 are struck from third rectangular portion 78 and are adapted to receive tabs 86 and 88 on divider panels 64 and 65 when the tray is in erected position.

A fourth rectangular portion 90 extends from forward edge 80 of rectangular portion 78 and is adapted to project rearwardly therefrom to constitute the bottom spacer panel. A panel portion 92 extends from edge 94 of rectangular portion 90 and forms the bottom flap member 40 in the completed tray. The side edges 96, 98 of panel portion 92 are serrated to afford better gripping action.

A panel portion 100 extends from edge 82 of rectangular portion 62 and is adapted to form the top spacer panel. A second panel portion 102 extends from the edge 104 of panel portion 100 and forms the top flap member.

In assembling the blank prior to shipment the rectangular portion 90 is glued to panel portion 100 and rectangular portion 92 is glued to panel 102 by means of spaced bands 106 of adhesive which run perpendicularly to the long dimension of the rectangular portion 92. With the tray in flat condition and glued as set forth above, the 70

front panel 28 will be in a horizontal plane in alignment with the top portion 12 and the bottom portion 30 will bear flat against these two portions of the tray.

As illustrated in FIGURE 2, when it is desired to erect the tray the divider panels 16 and 18 are swung downwardly thereby causing the bottom 30 to assume a curved shape generally corresponding to that of the lower edge of the divider panels. At the same time the front panel 28 swings downwardly as indicated by the arrow from its flat position such as it was in when the tray was shipped. The divider panels are swung into position so that their tabs 50 and 51 will fit into apertures 52 and 53 respectively as best shown in FIGURE 4. The top and bottom flaps 36 and 40 are then folded downwardly as indicated in dotted lines in FIGURE 4 and the tray is then ready for use.

With the tray in fully erected condition it is now time to use the tray for its intended purpose. For this, attention is directed to FIGURES 3 and 5 of the drawings wherein the tray is shown as it is mounted on a vehicle door. The flaps 36 and 40 are placed down in space 110 formed between the windows molding 112 and the window glass 114. The spacer portion of the tray formed by top and bottom spacer portions 34 and 38 rests on the top horizontal portion 116 of the window molding 114. Thus, the bottom portion 30 of the tray will to a small degree rest on the window molding depending on the shape of same. A cup may be positioned in the tray as indicated in phantom in FIGURE 5.

The tray of this invention is generally made from paperboard, however, it is contemplated that plastic sheeting may be used.

I claim:

1. A collapsible tray adapted to be supported on a vehicle door or the like wherein there is a panel member and a glass member spaced therefrom, said tray comprising a top portion, a front panel extending downwardly from the forward edge of said top portion, a downwardly directed arcuate bottom portion extending from the low-

5
10
15

er edge of the front panel, said bottom portion extending rearwardly and upwardly and engaging the rearward edge portion of the top portion the combined width of the top portion and the front panel being equal to the width of the arcuate bottom portion so that tray may be shipped flat with the top portion and front panel lying against the bottom portion, a top spacer panel portion extending from the rear edge of the top portion, a bottom spacer panel extending from the rear edge of the bottom portion parallel to and coinciding with the top spacer panel, means securing the two spacer panels together, and flap means hingedly connected to the rearward edge of the spacer panels, said flap means being adapted to fit down between the panel member and the glass member to hold the tray in position on the vehicle door.

2. The invention as described in claim 1 and wherein the top portion has at least one opening therein adapted to receive food or a beverage container and at least one divider panel hingedly secured to the top portion and engaging the bottom portion to retain the tray in erected position.

3. The invention as described in claim 2 wherein the flap means comprises a flap extending from the rearward edge of the top spacer panel and a coinciding flap extending from the rearward edge of the bottom spacer panel and means for securing together the flaps and reinforcing the flap means.

4. The invention as described in claim 3 and wherein the flap extending from the bottom spacer panel is serrated along its side edge portions.
